MECHANISM FOR OPENING SHEETS

Filed Oct. 24, 1923

3 Sheets-Sheet 3

FIG. 3.

UNITED STATES PATENT OFFICE

ROBERT EDWARDS, OF MARTINS FERRY, OHIO

MECHANISM FOR OPENING SHEETS

Application filed October 24, 1923. Serial No. 670,513.

The invention described herein relates to certain improvements in the construction of mechanism for opening sheets described and shown in Letters Patent No. 1,372,013, 5 granted to me March 22, 1921.

It is characteristic of the patented construction that the small intermediate rolls must be held in position to grip the sheets by the foot lever for the reason that the small rolls 10 are arranged in such relation to the large rolls, i. e., a substantial distance at one side of a vertical plane coincident with the axes of the large rolls, that when sheets enter between the small and large rolls, a pressure is exerted 15 to force the small rolls from operative position. This dislodging pressure will, in case thicker sheets than the large rolls have been adjusted for are operated on, be so great that the weight of a man will be insufficient to 20 hold the small rolls in operative relation to the large rolls, and for this reason it is necessary to adjust the large rolls in case of considerable variation in the gauge of sheets to be operated on.

25 The invention described and claimed herein has for its object a construction of mechanism wherein the smaller rolls are arranged with their axes in or approximately in a vertical plane coincident with the axes of the 30 larger rolls, and the engagement of the several rolls with sheets is effected by the shifting of one of the larger rolls. The invention is hereinafter more fully described and claimed.

35 In the accompanying drawings forming a part of this specification Fig. 1 is a sectional elevation of an opening machine embodying the improvements claimed herein; Fig. 2 is a side elevation of a portion of the machine on 40 an enlarged scale; and Fig. 3 is a top plan view of the same.

In the practice of the invention, the driven rolls 1 and 2 have their necks or journals mounted on bearings 3 and 4 arranged in 45 windows in the housing 5. The bearing 3 for the upper roll consists of two connected members enclosing the journals of the roll and the upper member is connected by swivel joints to the lower ends of screws 6 which extend up through nuts mounted in the housing

as is the usual practice. On the upper ends of the screws are secured discs 8 provided with notches 7 adapted to be engaged by dogs or pawls 10 pivotally connected to collars 11 loosely mounted on the upper unthreaded end 55 portions of the screws. In order to secure unison of movement of the pawls and screws, the former are connected by a rod 12. One at least of the pawls is provided with a handle 13 extending down along the housing sufficiently far to be operated by the mill man.

Between the rolls 1 and 2 is arranged a pair of floating rolls 14 having diameters less than those of the rolls 1 and 2 and so supported as hereinafter described that their axes will be in 60 or approximately in a plane coincident with the axes of the rolls 1 and 2. As shown in Fig. 2 the journals of the rolls 14 are rotatably mounted in blocks 15 slidably mounted in windows in the housings 5 so that the rolls 70 can move up when a sheet passes in between the lower rolls 2 and the lower one of the pair 14, and also ensures that when a sheet is pressed against the upper roll of the pair by shifting the roll 1, another sheet will be equally gripped between the lower roll of the pair 75 and the roll 2.

In order to guide sheets into the bite of the rolls, a suitable guide 15 is arranged in front of the pair of rolls 14. This guide is preferably formed by a roller having its journals loosely mounted in the blocks 15 as shown in Fig. 2. As shown, this roll 16 is so arranged relative to the rolls 14 that its axis must be in 80 a horizontal plane passing between the rolls 14 and it is preferably formed of such a diameter that the sheets being supported will be tangential to such roll under normal conditions.

In operating this mechanism sheets adhering one to the other are opened by hand at one end or side and are then fed to the machines, the sheets passing on opposite sides of the guide and their ends entered between the roll 1 and the upper roll of the pair and between 95 the lower roll 2 and the lower roll of the pair. The handle 13 is then operated to move the roll 1 down, whereby the sheets will be gripped and drawn forward, separation being effected by the roller 16. 100

It is characteristic of the construction shown herein that the sheets are pulled apart, that is, the lines of pull diverge and it is only when the sheets are more than usually adherent that the roll 16 will operate as a wedge supplementing the divergent pulls on the sheets.

5 I claim herein as my invention:

1. In a machine for opening packs of sheets the combination with a pair of driven rolls of a plurality of rolls disposed intermediate said driven rolls and adapted to cooperate therewith, the axes of said last named rolls being in a plane substantially coincident with the axes of said driven rolls and being further adapted for displacement relative to the driven rolls in response to variations in the thickness and number of sheets passing between the driven and intermediate rolls.
- 10 2. In a machine for opening packs of sheets the combination with a pair of driven rolls of a plurality of rolls disposed intermediate said driven rolls and adapted to cooperate therewith, the axes of said last named rolls being in a plane substantially coincident with the axes of said driven rolls and being further adapted for vertical movement in response to variations in the thickness and number of sheets passing between the driven and intermediate rolls.
- 15 3. In a machine for opening packs of sheets, the combination of a pair of driven rolls, two rolls arranged intermediate the driven rolls with their axes continuously in or approximately in a plane coincident with the axes of the driven rolls, the intermediate rolls being movable vertically, means for moving one of the driven rolls vertically to adjust the machine for opening packs of sheets of different thicknesses, and a guide roller arranged immediately in front of said intermediate rolls.
- 20 4. In a machine for opening packs of sheets, the combination of a housing, a pair of driven rolls journaled in the housing, blocks mounted for vertical movement only in the housing, two rolls arranged intermediate the driven rolls with their axes continuously in a plane coincident with the axes of the driven rolls and journaled in said blocks, and means for moving one of the driven rolls vertically to adjust the machine for opening packs of sheets of different thicknesses.
- 25 5. In a machine for opening packs of sheets, the combination of a housing, a pair of driven rolls journaled in the housing, blocks mounted for vertical movement only in the housing, two rolls arranged intermediate the driven rolls with their axes continuously in a plane coincident with the axes of the driven rolls and journaled in said blocks, and means for moving one of the driven rolls vertically to adjust the machine for opening packs of sheets of different thicknesses.
- 30 6. In a machine for opening packs of sheets, the combination of a housing, a pair of driven rolls journaled in the housing, blocks mounted for vertical movement only in the housing, two rolls arranged intermediate the driven rolls with their axes continuously in a plane coincident with the axes of the driven rolls and journaled in said blocks, and means for moving one of the driven rolls vertically to adjust the machine for opening packs of sheets of different thicknesses.
- 35 7. In a machine for opening packs of sheets, the combination of a housing, a pair of driven rolls journaled in the housing, blocks mounted for vertical movement only in the housing, two rolls arranged intermediate the driven rolls with their axes continuously in a plane coincident with the axes of the driven rolls and journaled in said blocks, and means for moving one of the driven rolls vertically to adjust the machine for opening packs of sheets of different thicknesses.
- 40 8. In a machine for opening packs of sheets, the combination of a housing, a pair of driven rolls journaled in the housing, blocks mounted for vertical movement only in the housing, two rolls arranged intermediate the driven rolls with their axes continuously in a plane coincident with the axes of the driven rolls and journaled in said blocks, and means for moving one of the driven rolls vertically to adjust the machine for opening packs of sheets of different thicknesses.
- 45 9. In a machine for opening packs of sheets, the combination of a housing, a pair of driven rolls journaled in the housing, blocks mounted for vertical movement only in the housing, two rolls arranged intermediate the driven rolls with their axes continuously in a plane coincident with the axes of the driven rolls and journaled in said blocks, and means for moving one of the driven rolls vertically to adjust the machine for opening packs of sheets of different thicknesses.
- 50 10. In a machine for opening packs of sheets, the combination of a housing, a pair of driven rolls journaled in the housing, blocks mounted for vertical movement only in the housing, two rolls arranged intermediate the driven rolls with their axes continuously in a plane coincident with the axes of the driven rolls and journaled in said blocks, and means for moving one of the driven rolls vertically to adjust the machine for opening packs of sheets of different thicknesses.

In testimony whereof, I have hereunto set my hand.

ROBERT EDWARDS.
